UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

Safety Attachment for Shipping-Tanks

1,256,158.

Specification of Letters Patent. Patented Feb. 12, 1918.

Application filed June 14, 1918. Serial No. 103,652.

To all whom it may concern:

Be it known that I, ALLEN E. OSTRANDER, residing at Ridgewood, Bergen county, State of New Jersey, and being a citizen 5 of the United States, have invented certain new and useful Improvements in Safety Attachments for Shipping-Tanks, of which the following is a full, clear, and exact description, such as will enable others skilled 10 in the art to which it appertains to make and to use the same, reference being had to the accompanying drawings, which illustrate the preferred form of the invention, though it is to be understood that the invention is not limited to the exact details of 15 construction shown and described, as it is obvious that various modifications thereof within the scope of the claims will occur to persons skilled in the art.

20 In said drawings:

Figure 1 is a vertical sectional view, the section being taken through the supporting beams or girders, through the bottom shell of a tank and through the discharge nozzle 25 and cap therefor, hereinafter referred to;

Fig. 2 is an elevational view partly in section, showing a fragment of the tank with the discharge nozzle secured thereto, the lower portion of the figure being shown in 30 section; and

Fig. 3 is a sectional view, the section being taken on line 3—3 of Fig. 2, looking in the direction indicated by the arrows.

The invention relates generally to shipping and storing vessels or tanks, and particularly to safety attachments for caps adapted for connection with the discharge nozzles or pipes leading from such tanks.

The invention is applied specifically to the 40 discharge nozzles of tanks such as are usually made as parts of railway tank cars and provides means whereby caps for such discharge nozzles are so attached to the support for the tank that when the cap is released, gravity will cause it to swing to one 45 side of, and clear of, the lower end of the nozzle, thereby providing for an unobstructed passage of fluid from the tank; at the same time maintaining the cap in such 50 convenient relation to the nozzle that it is readily accessible for replacement, when required.

It is common practice to provide in tank cars, supporting sills, as A, above which is 55 carried a tank B provided with a discharge

nozzle indicated generally by the reference character C, and though the nozzle in the present instance is novel, no claim is made in this application thereto.

To the lower end of discharge nozzles of 60 tank cars, a cap, similar to the cap D, is attached to close the lower end of such nozzles, and a suitable valve, as E, is positioned within the tank and is connected with suitable operating means therefor, which are 65 common in the art and are not herein illustrated.

The caps or closures D are frequently lost in service and to avoid this, novel means of support therefor have been provided comprising 70 a yoke or closure carrier which includes the arms 4, each of which is passed through a perforation in one of the flanges of the supporting sills A and there secured by upsetting an upper end of such arm, as indicated at 5, or providing nuts 6, which may be secured to the upper ends of such arms, or both may be provided, as desired. The arms pass thence downwardly obliquely, as best shown in Fig. 2, where they 75 are looped at 7, for the reception of the interlocking eyes 8 of the loop 9, which encircles the reduced portion 10 of the cap D above the enlargement of such cap, so that the cap is free to rotate for the purpose of 80 securing it to the lower screw-threaded end portion of the nozzle C.

The loops are long enough to permit the cap to be screwed on and off the nozzle, and when the cap is unscrewed from the nozzle, 90 it will drop by gravity to the position indicated in broken lines in Fig. 2, due to the eccentric relation of the support for the arms with relation to the collar of the outlet valve.

As thus supported, the cap is removed from the path of the discharging fluid passing out of the outlet nozzle, and it is also supported high enough from the track to avoid accidental contact with obstructions which 100 might tend to release the cap from its fastening.

The loops 7 are sufficiently long vertically to permit the cap D a sufficient freedom of movement for ready attachment to, and detachment from, the nozzle C.

In the present instance, the lower flange a of the girder or sill A, is provided with openings of considerably greater diameter than the thickness of the arms 4, and rest- 110

ing on such flanges are washers 12, upon which the nuts 6, before referred to, are supported, thus affording ample clearance for the arms 4 in their movement from the full line position indicated in Fig. 2, to the dot and dash position indicated in the same figure.

It will be noted that the lower end of the discharge nozzle is provided with both internal and external screw threads. This provision is so that, if desired, a plug may be substituted for the cap D and secured to the lower end of the discharge nozzle by screw connection with the interior thereof, instead of by connection with the exterior, as shown. Both types of closure are common in the art, but only one is illustrated in the drawings.

What I claim is:

20 1. In combination in a device of the character described, a shipping or storage vessel, a support therefor, a discharge pipe or nozzle communicating with the interior bottom portion of said vessel, oscillatory means 25 mounted on said vessel-support at a distance from said nozzle and having spaced lower portions, a cap-retainer connecting said spaced portions, a cap rotatable in said retainer, said means being movable into unbalanced position to locate said cap for attachment to the lower portion of said nozzle and reversely movable to remove the cap from the discharge path when it is detached.

35 2. In combination in a device of the character described, supporting girders, a tank mounted thereabove, a discharge nozzle communicating with the interior of the tank and depending between said girders to be 40 protected thereby, a cap for attachment to said nozzle below said girders, and a loosely connected cap support having opposite terminal portions connected to different girders and an intermediate portion loosely 45 mounting said cap, said cap-support being hung at a distance from said nozzle but being movable toward the nozzle into an unbalanced position, said cap when disconnected from said nozzle moving with its 50 support to fall to one side of the discharge end of said nozzle.

55 3. In combination in a device of the character described, a shipping or storage vessel, a support therefor, a discharge nozzle communicating with the interior of said vessel through the bottom portion thereof, a closure adapted to be rotatably secured to the lower end portion of said discharge nozzle, and a swaying structure of substantial 60 rigidity connected with said vessel-support to swing away from but movable toward said nozzle and including separated portions loosely connected by a closure-holder rotatably mounting said closure, said swaying 65 structure being adapted to swing said cap

to one side of said nozzle when the cap is disconnected therefrom.

4. In combination in a device of the character described, a shipping and storage vessel, a support therefor, a discharge nozzle 70 communicating with the interior of said vessel and depending below said support, a closure for the discharge end of said nozzle and an eccentrically mounted closure-carrier comprising spaced oscillatory arms connected with said support and a closure-retainer 75 connecting said arms.

5. In combination, a shipping or storage vessel, a structure underlying and supporting the same, a discharge nozzle for said 80 vessel depending therebelow, a closure for the lower end of said nozzle, means encircling said closure, and means of substantial rigidity having oscillatory support from the vessel-supporting means at a side of said 85 nozzle and movable to be unbalanced to carry said closure into juxtaposition to said nozzle, and reversely movable to permit the closure to be swung to and supported at one side of said discharge nozzle when the 90 closure is released therefrom.

6. In combination in a device of the character described, a shipping or storage vessel, spaced sills supporting the same, a discharge nozzle extending below said sills, a 95 closure for the lower end of said nozzle, and suspended means comprising depending oscillatory arms supported at their upper portions from said sills at a side of said nozzle and a cross member connecting their 100 lower portions, said closure being rotatively mounted in said member and attachable to said nozzle, said suspended means being movable against gravity to position said closure near said nozzle and being adapted 105 to swing to carry said closure to one side of the discharge nozzle when disconnected therefrom.

7. In combination in a device of the character described, a shipping or storage vessel, spaced sills supporting the same, a discharge nozzle extending between said sills, a closure for the lower end of said nozzle, and a suspended closure-carrier comprising 110 arms depending from and pivotally connected to said sills and a cross member connecting said arms and mounting said closure to be moved for attachment to said nozzle, said closure-carrier being inclined against gravity when said closure is connected to said 115 nozzle and being adapted to swing said closure away from said nozzle when it is disconnected therefrom.

8. In combination in a device of the character described, a tank, a discharge nozzle 120 depending below said tank, a closure for the nozzle, a support spaced from and independent of said nozzle, and a closure-carrier of substantial rigidity having a plurality of 125 pivotal connections with said support at 130

one side of said nozzle, whereby opposing reaction from its different pivotal connections causes said closure to have a prescribed path of movement, and also being movable toward said nozzle into unbalanced position, said closure being operably mounted in said carrier for connection to said nozzle and said carrier being adapted to positively carry said closure in the prescribed path to one side of said nozzle when disconnected therefrom.

9. In combination in a device of the character described, a tank, a discharge nozzle depending below said tank, a closure for the nozzle, a support spaced from and independent of said nozzle, and a closure-carrier comprising spaced rigid members pivoted to said support and a cross member rockably attached to said pivoted members and mounting said closure for connection to said lower portion of the nozzle, said carrier being adapted to be inclined toward said nozzle and operable by gravity to positively carry said closure in a predetermined path

away from said nozzle when it is disconnected therefrom, said closure being rockable in its carrier.

10. A tank and a discharge nozzle depending therefrom, in combination with a cap for said nozzle, a support and a gravity operable yoke pivotally connected to said support at a distance from said nozzle and including a cap-retainer and pendent members of substantial rigidity connected therewith continuously holding said retainer in approximate horizontal position when disconnected from the nozzle, said yoke being movable toward said nozzle into unbalanced position and being adapted to positively carry the cap away from the nozzle when it is disengaged therefrom.

In witness whereof I have hereunto set my hand in the presence of two witnesses.

ALLEN E. OSTRANDER.
